United States Patent

Des. 241,299

Patented Sept. 7, 1976

241,299

PICTURE FRAME

Louis M. Ohls, Tulsa, Okla., assignor to Travis World, Inc.

Filed Sept. 26, 1974, Ser. No. 509,798

Term of patent 14 years

Int. Cl. D6—07

U.S. Cl. D6—235

Fig. 1

Fig. 2

Fig. 3

Fig. 4

Fig. 5

FIG. 1 is a front elevational view of a picture frame showing my design;

FIG. 2 is a right-hand elevational view;

FIG. 3 is a bottom plan view;

FIG. 4 is a rear elevational view; and

FIG. 5 is a sectional view taken on line 5—5 of FIG. 4.

I claim:

The ornamental design for a picture frame, substantially as shown and described.
